UNITED STATES PATENT OFFICE.

JOSEPH P. LAWLOR AND JAMES I. SEAY, OF MEMPHIS, TENNESSEE

METHOD FOR INSTALLING WELL STRAINERS.

Application filed January 13, 1926. Serial No. 80,963.

This invention relates to methods of installing a well strainer and casing in a well bored through the overlying strata of earth, rock or other material as the case may be, 5 and into water bearing sand and has especial reference to the method of installing the strainer portion of the casing in the sand.

It further relates especially to the method for installing such a strainer made up of a 10 number of individual units preferably of concrete, tile or other similar material.

The objects of this invention are to provide a method for lowering, guiding and aligning the unit sections while they are being placed in the well; for so removing the sand to permit sinking of the strainer as to provide an enlarged space around the strainer; to hold back the sand, surrounding the space so formed, with coarser 20 material; to seal off the bottom of the strainer and to remove the guiding and lowering means after the unit sections are surrounded and held by the enveloping gravel casing.

25 We accomplish these objects as will be more fully hereinafter set out in the drawings, specification and claims.

In the drawings:

30 Figs. 1 to 6 inclusive show progressive steps in installing a well by our improved method.

Fig. 1 is a vertical section of the well, with an exterior casing sunk to the water bearing sands and with a portion of the 35 strainer assembled ready to lower therein.

Fig. 2 is a similar view, with the strainer lowered to the sand and one section of the solid casing of the well in place.

40 Fig. 3 is a similar view with the strainer surrounded by gravel ready to lower into the sand.

Fig. 4 illustrates the next step with the strainer partially lowered into the sand.

45 Fig. 5 shows the strainer lowered to hard pan or such depth as it may be desired to lower it and the bottom closed with a concrete plug.

Fig. 6 shows a completed well with the 50 lowering and guiding means removed.

Fig. 7 is a similar view of the well showing a modified method of lowering the strainer and well casing assembly therein.

55 Fig. 8 is an enlarged view of the lowering pipe and point.

Referring now to the drawings in which

the various parts are indicated by numerals, 1 designates a well opening which has been sunk in any usual manner through the overlying strata to the water bearing sand. 2 indicates the casing for the well through 60 this overlying strata. 3 is a hollow truncated cone shaped point preferably of cast iron having a cutting edge 4 which is of diameter larger than the outer diameter of the strainer, but slightly less than the inside 65 diameter of the well casing. 5 is a lowering and guiding member which is ordinarily an iron or steel pipe preferably having both a smooth exterior and interior surface, which pipe is ordinarily made up of a number of 70 short sections, screwed together with halved joints 5^A. The lower end of the pipe 5 is screwed into the upper threaded end of the cone 3. Preferably the sections of the pipe 5 are left-hand threaded at the joints 5^A 75 and in such case the lower end of the pipe is provided with a right-hand threaded end and the upper end of the cone 3 is correspondingly threaded.

6 are the strainer units which preferably 80 initially are annular rings of concrete, tile or similar material which are provided with suitable passages, not shown, which will permit the ingress of the water. Resting on these units 6 which make up the strainer sections are well casing sections 7 which preferably are not provided with water passages.

These sections may be otherwise entirely 85 similar to the sections 6 but preferably are longer. The lower one of the strainer units 6 is adapted to fit firmly on the upper surface 8 of the cone 3 which surface is properly shaped for that purpose. If desired, the various sections may be secured together in 90 any usual or desired manner and may likewise be secured to the cone 3.

9 is the water bearing sand and 10 gravel forming an envelope around the strainer sections 6. 11 is a supporting block and 12 100 are supporting clamps. In the modified form shown in Fig. 7, 14 is a column of sand formed by filling up substantially to the surface of the ground the initial well opening which was bored through the overlying strata.

The method of installing a well casing and strainer is as follows:—First, a well is sunk through the overlying strata down to the water bearing sand in any usual manner and ordinarily this well is provided 110

- with an outer casing 2. In the event that rock is the overlying material it may not be necessary to put in such casing and if so, or if for any other reason the well opening is satisfactorily self-supporting, this casing may be omitted. After the well has been completed to the water bearing sand, the hollow point 3 is placed on the blocks 11, over, and in line with, the well opening. 10 A section of the lowering pipe 5 is then screwed into the cone 3, and thereafter a number of strainer units 6 are placed around the pipe 5, the lower one resting on the upper surface 8 of the cone and the others 15 being each superposed thereabove. These strainer units preferably embrace the pipe 5 closely so that they may be aligned thereby during lowering. The pipe 5 supporting these units is then lowered into the well 20 by any usual well rigging adapted thereto until the top of the first set of strainer units come approximately level with the surface of the ground. It may then be supported by clamps 12 and additional units be placed 25 resting on the clamps. When this has been done, the pipe 5 is again supported by the rigging, the clamps removed and the pipe is further lowered, this process being repeated until the cone 3 reaches and rests on the 30 water bearing sand 9. Gravel 10 is then put into the well to form an envelope surrounding and extending somewhat above the top of the upper strainer section, and thereafter sand is removed by bucketing or 35 pumping through the pipe 5 until the cone 3 reaches hard pan, or such depth in the water bearing sand as may be desired.
- Prior to this removal of the sand, the clamp 12 as shown in Fig. 2 is clamped 40 down against the top well section 7 so that there may be no possibility of the sections separating due to the supporting power of the enclosing gravel, during sinking.
- During the sinking of the casing, the 45 gravel envelope 10 will follow down with the cone, filling the space around the strainer which is left by the removal of the sand. If desired, additional gravel may be added in order that at all times the gravel envelope may not only cover the strainer units but may extend slightly above and along the 50 solid portion of the casing.
- When the desired depth has been reached, the cone 3 is filled in with a concrete plug 55 13 which is allowed to harden and thereafter the pipe 5 is unscrewed and removed from the well.
- In some cases, it is found that the bottom on which the point rests satisfactorily 60 seals the cone and in such cases, the concrete plug may be omitted.
- In the modification shown, in Fig. 7, the well is sunk to the water bearing sand in the usual manner, and is then re-filled or 65 partly refilled with sand. The point 3 is then preferably placed directly on this sand filler and the pipe 5 screwed into place. Strainer units 6 are then placed therearound and thereafter the assembly is lowered in the well by removing the sand filling instead of using the ordinary well rigging hereinbefore mentioned. In this case strainer units and solid sections are added as previously described.
- It will be especially noted that during the 70 lowering of the strainer units they are kept constantly in alignment by the lowering pipe 5 and that before the lowering pipe 5 is removed the envelope 10 has entirely surrounded the units and is supporting them against any movement which would cause them to get out of alignment.
- The pipe 5 not only serves as a guide for the concrete strainer and casing, but 75 also serves as a protection against the injury of the strainer while removing the sand during the bailing process. Pipe 5 prohibits the bailing apparatus from striking against the concrete strainer's interior surface while bailing out the sand.
- Having now fully described our invention, 80 what we claim and desire to secure by Letters Patent in the United States is:—
1. The method of installing a casing in a well, comprising, removably securing an enlarged hollow point on the lower end of a lowering and brinding pipe, assembling and lowering strainer units and well casing units closely surrounding said pipe, and supported by said point to the water bearing sands, surrounding the strainer units with a gravel envelope, removing the sand through the central pipe and permitting the gravel enveloped units to lower in the sands as the sand is removed, sealing the cone and removing the central guiding and lowering pipe. 90
  2. The method of installing a casing in a well, comprising, removably securing an enlarged hollow point on the lower end of a lowering and guiding pipe, assembling and lowering a strainer and well casing surrounding said pipe, and supported by said point to the water bearing sands, removing the sand through the central pipe and permitting the assembly to lower in the sands as the supporting sand is removed, and removing the central guiding and lowering pipe. 100
  3. The method of installing a casing in a well, comprising, removably securing an enlarged hollow point on the lower end of a lowering and guiding pipe, assembling strainer units and well casing units on and supported by said point and surrounding said pipe, lowering the assembly in the well, adding additional units, until the water bearing sands are reached, surrounding the strainer units with gravel to envelope the units, removing the sand through the cen- 110

tral pipe and permitting the assembly including the gravel enveloping the units to lower as the sand is removed, adding additional units as necessary, and removing the central guiding and lowering pipe.

4. The method of installing a casing in a well, comprising, placing supporting sand in said well, removably securing an enlarged hollow point, on the lower end of a lowering and guiding pipe, assembling strainer units and well casing units surrounding said pipe, and supported by said point, removing the supporting sand through said pipe to lower the assembly to the water bearing sands, surrounding the strainer units with gravel to envelope the units, removing the water bearing sand through said pipe and permitting the gravel enveloped units to lower in the sands, sealing the cone and re-

moving the central guiding and lowering 20 pipe.

5. The method of installing a casing in a well, comprising, placing supporting sand in said well, removably securing a hollow point on the lower end of a lowering and 25 guiding pipe, assembling a strainer and well casing, on, and supported by said point, lowering the assembly by removing the supporting sand and water bearing sand through said pipe and permitting the assembly 30 to lower as the sand is removed, adding additional units as necessary, and removing the central guiding and lowering pipe.

In testimony whereof we have hereunto set our names.

JOSEPH P. LAWLOR.
JAMES I. SEAY.
